WATERFLOW RETARD ALARM

Clarence C. Johnson, New York, N. Y., Richard M. Hopkins, Rutherford, N. J., and Richard F. Spamer, Lynbrook, N. Y., assignors to American District Telegraph Company, New York, N. Y., a corporation of New Jersey

Application February 24, 1932, Serial No. 594,798

22 Claims. (Cl. 177—382)

This invention relates to retarded alarms for water-flow-operated sprinkler-systems, and more particularly to retarding means for electric alarm systems to prevent alarm from water-hammer in the sprinkler system though it is noted that in some of the claims the invention is not limited to sprinkler means nor to electric means, nor in some respects even to retarding means.

Objects of the invention are to improve generally the simplicity and efficiency of such apparatus and to provide a device or apparatus of this kind which is economical, durable, sensitive and very reliable in operation, and economical to manufacture.

Another object of the invention is to provide a completely supervised retarded system of this kind for one or a large number of flow detectors which automatically places itself in alarm-sending condition after a line-break, to be in full alarm-sending condition both before and after both occurrence and repair of the break.

Another object of the invention is to provide a very quick acting alarm, which at the same time will not be actuated by water hammer.

Still other objects of the invention will appear as the description proceeds; and while herein details of the invention are described and claimed, the invention is not limited to these, since many and various changes may be made without departing from the scope of the invention as claimed in the broader claims.

The inventive features for the accomplishment of these and other objects are shown herein in connection with an improved retarded alarm system which, briefly stated, includes service or house lines between and connecting an alarm means and a current source in series circuit, thus to supervise the circuit and hold the alarm means against operation, the alarm operating on open circuit. Water-flow-operated normally open detector switches connect said lines, and when closed, short-circuit and operate the alarm means. The alarm means also operates on a break in the house lines, which operation causes normally open shunting switches to close and shunt said lines respectively, to adapt the line for operation of the alarm means, after the break, thereby to set in operation an additional fire alarm mechanism.

To prevent operation by water hammer, a water-hammer-operated cut-out switch simultaneously shunts and cuts out the detector switch elements of one line, thus disabling the detector switch. This cut-out switch is controlled by an actuating means including a surge pipe,

communicating with the sprinkler-system supply conduit, and provided with an air chamber and an intermediate constriction, and closed bellows respectively communicating with said pipe on both sides of the constriction, and adapted to operate a pair of electrically conductive levers.

One lever has opposed contacts, the other lever having a contact portion disposed between said opposed contacts, whereby unequal operation of the bellows causes contact and completes an electric circuit to energize an electro-magnet for operating the cut-out switch, thus preventing operation of the alarm means.

In the accompanying drawings showing, by way of example, one of many possible embodiments of the invention,

Fig. 1 is a diagrammatic showing of the conduits, water-hammer-operated actuating means and the electric alarm system; and

Fig. 2 is a less-detailed diagram of the electric circuit of the alarm system and cut-out switch.

The system as a whole

This invention is shown in combination with a sprinkler system main conduit 5, feeding any number of branch conduits 6 feeding sprinkler heads (not shown) which discharge in time of fire and cause flow in the conduits, causing the one or more of the fan shaped flow detectors 7 to deflect and close switches 8, 9 and 8', 9' respectively.

In case of fire, these switches short-circuit a supervised alarm circuit, causing a fire alarm. In case of water hammer, these switches are cut-out and thereby disabled by water-hammer operated cut-out means forming a part of this invention.

The supervised circuit

The circuit is clearly shown by Fig. 2; Fig. 1 shows more detail, both figures being diagrammatic.

A trouble alarm 10 is set off by a retarded relay 11, both being similar in operation to that shown by the Hopkins Patent No. 1,398,594 issued Nov. 29, 1921, except that the present electro-magnet 12 relay is normally energized and operates when deenergized to let fall the retarded weight 13, in time to release the alarm 10. Therefore, the present relay is up-side down as compared with the patent.

The relay is held inoperative and energized by current from a source 15, the supervising circuit being traced through conductors 17, normally closed cut-out switch 18, 19, house line conductor 55

29, switch element 9', house line conductor 21, element 9, house line conductor 22, cut-out switch 23, 24, conductor 28, to normally closed switch 29, 30, conductor 31, electromagnet 12, house line conductor 32, switch element 8', house line conductor 33, element 8, house line conductor 34 normally closed switch 35, 36, conductor 37, source 15. Thus the electromagnet is held energized, the weight 13 held raised and the trouble alarm 10 held against operation.

With the parts in this condition and without water hammer, flow in one or more conduits 6 causes closure of one or more detector switches 8, 9 or 8', 9', thus short circuiting the solenoid 12, causing alarm as will be explained.

The switch A is the water hammer operated cut out switch, as will be explained, and were this switch not used, the above circuit would be traced directly from conductor 17, to element 9', 20 conductor 21, element 9 to element 29. As will be explained, this switch A is merely a cut-out for switch elements 9, 9' to prevent them from operating the system as a result of water hammer.

25 Line break

Should there develop a line break as in line conductors 28, 21, 22, 32, 33, 34, as for instance breaks at x or y, the above supervising circuit would be broken, and the magnet 12 deenergized, 30 allowing the weight 13 to slowly descend, in time causing the lifting of the release lever 40, allowing the alarm 10 (Fig. 1) to unwind to send a trouble signal and to unwind until the cam projection 40' on the winding arbor 41 engages the 35 insulated bump 42 carried on switch member 35, of the diagrammatically shown multiple switch B consisting of elements or members 35, 36, 44, 30, 29, 45, wherein the members 35, 29 are shown connected by an insulating bar 46. It is understood that this showing is strictly diagrammatic 40 for purposes of clearness.

The tension and set of the elements of switch B is such that at the midposition of members 35, 45 29 all of the switches are closed, and the projection 40' revolves until this condition is effected, this effects shunts around the lines and the breaks x and y, again closing the circuit, so that the circuit may be traced as follows: source 15, 50 conductors 17, shunt conductor 47, switch elements 45, 29, 30, conductor 31, electromagnet 12, conductor 32, shunt conductor 48, switch elements 44, 35, 36, conductor 37, source 15.

Thus the circuit is complete, electromagnet 12 is energized, and the retard relay is drawn to 55 silencing position. This would immediately silence the alarm 10, except that these alarms, as shown in said patent, run until the required trouble signal is completed and then stop unless the lever 40 is again raised or remains raised.

60 Fire alarm with broken line

In this new condition, the system is still in condition to send a fire signal by means of water flow effecting the closure of one or more detector 65 switches 8, 9 or 8', 9'. Should one of these switches thus close, the electromagnet 12 will be short circuited, again releasing the alarm 10.

If the break is at y and switch 8, 9 is closed, the circuit may be traced as follows: source 15, 70 conductors 17, 47, elements 45, 29, conductor 28, elements 24, 23, conductor 22, elements 9, 8, conductor 34, elements 35, 36, conductor 37, source 15.

If the break is at y and switch 8', 9' is closed, 75 the circuit may be traced as follows:—source 15, each having an end fulcrum 67 and intermedia-

conductor 17, elements 18, 19, conductor 20, elements 9', 8', conductors 32, 48, elements 44, 35, 36, conductor 37, source 15.

Other circuits with the break at x will be understood from the foregoing.

5

Sending the fire alarm

If as just stated, a fire should cause water flow, and one of these circuits should be formed, short-circuiting and deenergizing electromagnet 12, the 10 alarm 10 would further unwind, causing the projection 40' to further operate the switch B, maintaining the switches 35, 44 and 29, 45 still closed, but opening switches 36, 35 and 30, 29, and cutting out the electromagnet 12.

15

At this time there would be no trouble signal, since the untoothed portion 49 of the signal wheel would be opposite the pen 50, but the opening of the switch 35, 36 breaks the circuit through conductor 37 causing current to flow through 20 conductors 52, 53 and the normally deenergized electromagnet 54 of the fire alarm 55 raising the armature 56, releasing the alarm mechanism and sending the fire alarm. In this condition, the circuit may be traced as follows: source 15, 25 conductor 17, and thence as above explained through a switch 8, 9 or 8', 9' and to conductor 34, thence through conductor 52, electromagnet 54, conductors 53, 37, source 15.

After a repair is made the serviceman restores 30 the parts to the position shown in the drawings, after which the operation is the same as if the line had never been broken.

Fire alarm with unbroken line

35

If the line be unbroken, the sending of the fire alarm will be easily understood from the foregoing. With unbroken line the parts are as in the drawings and the closure of one or more detector switches, short circuits and deenergizes the 40 electromagnet 12 as above explained, sending in a trouble alarm, closing switches 29, 45, and 35, 44. However, as the detector switches will remain closed on account of the continued flow to the 45 sprinkler heads, the electromagnet 12 will continue to be short circuited and deenergized, thus causing the continued revolution of the projection 40 and the opening of the switch 29, 30 and switch 35, 36 as above explained, thus sending current through the electromagnet 54 and operating 50 the fire alarm.

The water hammer operated cut out

The above description has assumed absence 55 of water hammer in the conduits. It is desirable to have the retard relay 11 set to act fairly quickly, so as not to greatly delay the sending of the alarm; and without the cut-out means, whatever hammer is in the conduits 6 operating one or more of the detectors and closing one or 60 more detector switches, might be sufficient to cause the sending of an alarm. Accordingly means are provided to cut-out and thereby disable the detector switches during water hammer.

65

This means comprises a surge pipe 60 communicating with the main conduit 5 and provided with a yieldable outer end closing means such as the air chamber 61 at one end and an intermediate constriction 62. Closed metallic 70 bellows 63, 64 communicating with said pipe on both sides of the constriction 62 are adapted to be expanded by pressure in the pipe and raise a pair of electrically conducting levers 65, 66 each having an end fulcrum 67 and intermedia-

75

ately connected as by a bar 68 to the active portion 69 of the bellows respectively. One lever for instance the lever 65 has a forked active end having inwardly adjustable opposed contacts 73, 74 adapted at times to be engaged by oppositely pointed contacts 76, 77 on the active end of the lever 66 and disposed between said adjustable contacts adjacent to, and just out of contact therewith, respectively.

Conductors 17, 18, 19 electrically connect said levers respectively in series with said source 15 and a solenoid 30 which operates the cut out switch A. Sudden pressure in said pipe 60 causes the bellows nearer the conduit to move the associated lever 65 more rapidly than the other, thereby making contact between adjacent contacts 74, 77 thereby to energize the solenoid and actuate the switch A.

The constriction 62 allows the pressure in the bellows and air chamber to remain normally equal, except when disturbed by water hammer, as above indicated, the constriction being so small that water-hammer pressure will not have time to be communicated to any considerable extent to the bellows 64.

The cut out switch

As already indicated, the switch A includes a pair of normally closed cut out switches 18, 19, and 23, 24 interposed respectively at both ends of the house line 20, 21, 22.

The switch A also includes a normally open shunt switch 18, 33 adapted when closed to shunt the current through the conductor 34 around that portion 20, 21, 22 of the house line which includes said cut out switches and the detector switch elements 9, 9', thereby disabling the detector switch.

When the water hammer operates to energize the electromagnet 30, the solenoid 85 is attracted, thus rocking the bell-crank lever 85, 86, raising the insulating block 87 on the end of the lever arm 88, thus raising the end of switch element 33, thus closing the shunt switch 33, 18 and raising switch elements 18 and 24, connected by the insulating bar 89, thereby opening the cut out switches 18, 19 and 23, 24, thereby to cut out and isolate the associated detector switch elements 9, 9' thereby to disable the detector switch, and to simultaneously shunt around such elements through the conductor 34.

With the switch elements 9, 9' thus entirely cut out, any closure of the switches 8, 9 and 8', 9' is ineffective, as no current can reach elements 9, 9'. Thus the solenoid 12 cannot be short circuited by closure of the switches 8, 9 or 8', 9', and water-hammer cannot be effective to send an alarm. Should a sprinkler head go off during water-hammer, the sending of the alarm would be delayed only for the short instant of the duration of the water-hammer.

If, during absence of water hammer, a number of sprinkler heads open, or if the number which opens is sufficient, the pressure in bellows 63 will drop enough to cause the closing of contacts 73, 76, thus momentarily maintaining the supervised circuit open. As the water continues to flow, the pressure in bellows 64 must finally become equal to the pressure in bellows 63, whereupon the arm 66 will take a midway position with respect to the arm 65, and contacts 73, 76 will be disengaged, resulting in the functioning of the magnet 12 and finally of the magnet 54 to send a fire alarm.

It has been found from years of field experi-

ence in thousands of sprinkler installations that no definite period of retarding can be established for all installations. Under some service conditions no retarding at all is required; while under other conditions a retarding time of several minutes would not prevent false alarms. A retard period of 8 to 10 seconds has been arbitrarily established; but where the surge conditions are severe additional means of delaying the operation of the alarm device are necessary. Thus if only 10 the retard means 10, 11 were used where water hammer might last more than ten seconds, the water hammer cut-out means is required. It is not desirable to lengthen the period of the retard means 11 to more than ten seconds, as it is not 15 desirable to delay the alarm more than necessary.

It is not desirable to omit the retard means 10, 11, as it performs many functions: It prevents the operation of the alarm 55 from the bouncing of the vanes 7 due to building vibration, foreign 20 bodies floating upward through the riser 6 or pounding on the pipe, any one of which conditions might, and in some cases does, cause the momentary closing of the switches 8, 9.

Also, the trouble alarm 10 causes the mechanical switching of the line circuits so that an alarm 25 can be sent where either or both of the supervised circuit lines are broken.

Another function of contact 73 is to render the system inoperative on backward flow due to a 30 prolonged surge, which would ultimately cause equalization of pressure in the bellows 61, 63, following a reduction in pressure due to a leaking city check valve, a very common source of trouble, which would cause the vane 7 to bounce. The 35 pressure in the chamber 61 would be higher (due to the surge) than that in the bellows 63 during the out flow, thus causing contacts 73, 76 to engage. The vanes 7 would be moved downwardly and if the flow stopped suddenly, as it frequently 40 does, the vane would swing upwardly to momentarily close the switches 8, 9.

I claim as my invention:

1. In combination, a conduit; an alarm; means operated by flow in the conduit to operate the 45 alarm; a surge pipe communicating with the conduit and provided with a substantially closed outer end and an intermediate constriction; closed bellows communicating with said pipe on both sides respectively of the constriction; a pair 50 of electrically conducting levers mechanically connected to the active portions of the bellows respectively and adapted to contact each other when either one of the bellows expands more than the other; and an electro-magnetic means 55 actuated by such contact to disable the alarm.

2. In combination, a conduit; a surge pipe communicating with the conduit and provided with closing means at the outer end and an intermediate constriction; a pair of closed bellows 60 respectively communicating with said pipe on opposite sides respectively of the constriction; a pair of electrically conducting levers mechanically connected to the active portions of the bellows respectively; one lever having opposed contacts, 65 the other lever having contacts disposed between said opposed contacts; and an electric circuit in which said levers are connected in series.

3. In combination, a surge pipe provided with closing means at the outer end and an intermediate 70 constriction; a pair of closed bellows respectively communicating with said pipe on opposite sides respectively of the constriction; a pair of electrically conducting levers mechanically connected to active portions of the bellows respec- 75

tively; one lever having opposed contacts, the other lever having a contact part disposed between said contacts; an electric circuit in which said levers are connected in series; and translating means operated by said circuit.

5. In combination, an alarm means; a source of current; lines between said source and means and connecting said alarm means and source in series circuit to hold the alarm means against 10 operation; a normally open detector switch connected and adapted to close to connect said lines, to short-circuit and operate the alarm means; normally open shunting switches closed by operation of said alarm means, and connected for 15 shunting said lines respectively, an alarm set in operation by the further operation of the alarm means.

6. In combination, a retarded alarm means; a source of current; lines between said alarm 20 means and source and connecting them in series circuit to hold the alarm means against operation; a conduit; a flow detector therein, a normally open detector switch adapted to be closed by said detector to connect said lines, to short-circuit and operate the alarm means; normally 25 open shunting switches closed by operation of said alarm means, and connected for shunting said lines respectively, a normally closed switch in one line between said source and detector switch; a fire alarm shunted around and short-circuited by said last named switch and adapted to operate when the switch is opened; means whereby further operation of the alarm means opens said normally closed switch operating the fire alarm; 30 and cut-out means operated by water-hammer in said conduit to simultaneously shunt and cut out the detector switch element of one line, the shunting taking place soon enough to prevent operation of the alarm means by the cutting out 35 of the switch element.

7. In combination, a retarded alarm means; a source of current; lines connected between said alarm means and source connecting them in series circuit to hold the alarm means against operation; a normally open flow-controlled detector 45 switch adapted to close to connect said lines to short-circuit and operate the alarm means; normally open shunting switches closed by operation of said alarm means, and connected for shunting said lines respectively, a normally closed switch in one line between said source and detector switch; a fire alarm shunted around and short-circuited by said last named switch and adapted to operate when the switch is opened; means 50 whereby further operation of the alarm means opens said normally closed switch operating the fire alarm; a pair of normally closed cut-out switches interposed in one line respectively on both sides of the detector switch; a normally open 55 shunt switch shunted around the cut out switches; and means for simultaneously closing the switch and opening the cut-out switches.

8. In combination, a retarded alarm means inoperative on closed circuit and operating when 60 open-circuited or short-circuited; a source of current; lines between said alarm means and source and connecting them in series circuit to normally hold the alarm means against operation; one or more normally open flow-detector-controlled detector-switches adapted when closed to connect 65 said lines to short-circuit and operate the alarm means; normally open shunting switches closed by operation of said alarm means, as in case of line break, for shunting said lines respectively around 70 the break, thereby to silence the alarm means

and leave the circuit in condition to short circuit and operate the alarm means on closure of the detector switch; a normally closed switch in one line between said source and detector switch; a fire alarm shunted around and short-circuited by 5 said last named switch and adapted to operate when the switch is opened; a normally closed switch in the other line between the detector switch alarm means; and means whereby further operation of the alarm means opens said normally closed switches operating the fire alarm and breaking the circuit through the alarm means.

9. In combination, water flow detectors; a closed circuit controlled thereby; a signal means 10 controlled by the circuit and set in operation by the breaking of said circuit or by said circuit on actuation of said detectors and set in further operation by actuation of the detectors after the break; a fire alarm set in operation only by said 15 further operation; and water hammer operated means for disabling the detectors during water hammer before and after said operations, thereby to prevent confusing water hammer operation with water flow operation, and to prevent 20 fire alarm from water hammer.

10. In combination, water flow detectors; a circuit controlled thereby; a signal means controlled by the circuit and set in operation by said circuit on circuit defect or actuation of said detectors 25 and set in further operation by further actuation of the detectors; a fire alarm set in operation by said further operation; and water hammer operated means for disabling the detectors during 30 water hammer before and after said operations, thereby to prevent confusing water hammer operation with water flow operation, and to prevent 35 fire alarm from water hammer.

11. An apparatus comprising a translating means; a source of current; lines between and 40 connecting said means and source in series circuit to hold the translating means against operation; a normally open switch having its elements connected to said lines respectively and adapted to close to connect said lines to short-circuit and operate the translating means; and normally open shunting switches closed by operation 45 of said translating means, and connected for shunting said lines respectively.

12. Apparatus as in claim 10 comprising a 50 translating device set in operation by the further operation of the translating means.

13. In combination, a sprinkler system having flow pipes; water flow detectors having flow vanes in said pipes; a closed supervised circuit 55 controlled by said detectors; a signal means controlled by the circuit and set in operation by the breaking of said circuit, or by said circuit on actuation of said detectors and set in further operation by actuation of the detectors after the 60 break; a fire alarm set in operation only by said further operation; and back flow operated means set in operation by prolonged back surge, before or after said operations, for disabling the detectors during said back surge to prevent operation 65 by the bouncing of the vane caused by sudden stoppage of said back surge, thereby to prevent confusing said bouncing of the vane with waterflow operation, and to prevent fire alarm before or after said break by said bouncing 70 of the vane.

14. In combination, sprinkler system flow pipes; waterflow detectors having flow vanes in said pipes; a closed supervised circuit controlled by said detectors; a signal means controlled by 75

the circuit and set in operation by the breaking of said circuit, or by said circuit on actuation of said detectors and set in further operation by actuation of the detectors after the break; a fire 5 alarm set in operation only by said further operation; and water hammer and back surge operated means for disabling the detectors during back surge and water hammer before and after said operations, thereby to prevent operation by 10 water hammer or by bouncing of the vanes from sudden stoppage of said back surge, thereby to prevent confusing vane bouncing and water hammer operation with water flow operation, and to prevent fire alarm from water hammer or 15 vane bouncing, before or after said break.

14. In combination, sprinkler system flow pipes; waterflow detectors having flow vanes in said pipes; a closed supervised circuit controlled by said detectors; a signal means controlled by 20 the circuit and set in operation by the breaking of said circuit, or by said circuit on actuation of said detectors and set in further operation by further actuation of the detectors after the break; a fire alarm set in operation only by said 25 further operation; and water hammer and back surge operated means for disabling the detectors during back surge and water hammer before and after said operations, said means comprising a switch comprising a single pair of switch elements closable to operate said disabling means; means whereby said switch is automatically closed during back surge and during water hammer, thereby to prevent operation by water hammer and by bouncing of the vanes from sudden 30 stoppage of said back surge, thereby to prevent confusing vane bouncing and water hammer operation with water flow operation, and to prevent fire alarm from water hammer or vane bouncing, before or after said break.

40 15. In combination, a sprinkler system having flow pipes; water flow detectors having flow vanes in said pipes; a closed supervised circuit controlled by said detectors; a signal means controlled by the circuit and set in operation by said 45 circuit on actuation of said detectors; and back flow operated means set in operation by prolonged back surge, before or after said operations, for disabling the detectors during said back surge to prevent operation of the signal by the 50 bouncing of the vane caused by sudden stoppage of said back surge, thereby to prevent confusing said bouncing with waterflow operation.

55 16. In combination, a normally energized alarm means adapted to operate when deenergized; a source of current; lines connecting said alarm means and source in series circuit to hold the alarm means against operation; a break in the line deenergizing and operating the alarm means; said alarm means being between the 60 lines; normally open detector switches spaced along intermediate portions of the respective lines and adapted to be closed to connect said lines to each other to short-circuit and operate the alarm means; and normally open shunting switches adapted to be closed by operation of said alarm means when deenergized, and connected and adapted when closed to shunt around said intermediate portions respectively, thereby 65 to restore said series circuit and energize and stop the alarm means, if the alarm means were operated by line break and the detector switches are open; said shunting switches when closed connecting both ends of said intermediate portions to the respective lines, whereby detector- 70 switch closure after such line break in one of

said intermediate portions, may again short circuit and operate the alarm means.

17. In combination, a normally energized alarm means adapted to operate when deenergized; a source of current; lines connecting said alarm means and source in series circuit to hold the alarm means against operation; a break in the line deenergizing and operating the alarm means; said alarm means being between the lines; normally open detector switches spaced 10 along intermediate portions of the respective lines and adapted to be closed to connect said lines to each other to short-circuit and operate the alarm means; normally open shunting switches adapted to be closed by operation of 15 said alarm means, and connected and adapted when closed to shunt around said intermediate portions respectively, thereby to restore said series circuit and energize and stop the alarm means, if the alarm means were operated by line 20 break and the detector switches are open; said shunting switches when closed connecting both ends of said intermediate portions to the respective lines, whereby detector-switch closure after line break in said intermediate portion and consequent shunting may again short circuit and operate the alarm means; an alarm set in operation by the further operation of the alarm means; and means to simultaneously cut out and shunt one of said intermediate portions and the 25 detector switch elements therein.

18. In combination, a conduit subject to slow pressure change and water hammer; an alarm means operated by flow in the conduit to operate the alarm; a surge pipe communicating with the 30 conduit and provided with a substantially closed outer end and an intermediate constriction; a pair of closed bellows, one communicating with said pipe on one side of the constriction and the other bellows communicating with the pipe on 35 the other side of the constriction; a pair of electrically conducting levers mechanically connected to the active portions of the bellows respectively and adapted to contact each other when either one of the bellows expands more than the other; and electric means actuated by such contact to 40 disable the alarm; said constriction allowing equilibrium to be established between said bellows when the pressure in the conduit slowly changes, thereby to prevent the disabling of the 45 alarm by said slow rise or fall in said pressure.

19. The combination of a surge pipe provided with an intermediate constriction and with an inner pressure opposing means at the outer end of the pipe; pressure-operated means respectively 50 communicating with said pipe on opposite sides of the constriction and adapted to be unevenly operated by liquid in the pipe when the liquid surges toward or from said outer end; and a translating means actuated by uneven operation 55 of the pressure means when one pressure operated means is operated more than the other, whereby said combination produces the new and better result that the translating means is operated by said surge when moving either toward or from 60 said outer end.

20. In combination, an alarm means held against operation by current passing therethrough and released for operation when said current is sufficiently reduced; a source of current; lines between said source and means and connecting said lines, alarm means and source in series circuit to hold the alarm means against operation; a normally open detector switch having its elements connected to said lines respec- 75

tively and adapted to close to connect said lines, to short-circuit and operate the alarm means; normally open shunting switches connected for shunting said lines respectively, and said elements connected thereto, when the shunting switches are closed, and adapted to be closed by operation of said alarm means when said operation is caused by a break in either of said lines, closure of the shunting switch around the break reestablishing the circuit and arresting the alarm means, leaving the alarm means in condition for further operation by the closure of the detector switch; additional alarm means; and means set in operation by the further operation of the first named alarm means operating the additional means.

21. In combination, a translating means held against operation by current passing therethrough and released for operation when said current is sufficiently reduced; a source of current; lines between said source and means and connecting said lines, alarm means and source in series circuit to hold the alarm means against operation, said translating means operating when not so held; a normally open detector switch having its elements connected to said lines respectively and adapted to close to connect said lines, to short-circuit, and operate, the translating means; normally open shunting switches connected for shunting said lines respectively, and said elements connected thereto, when the shunting switches are closed, and adapted to be closed by operation of said alarm means, whereby when said operation is caused by a break in either of said lines, the closure of the shunting switch shunts around the break and reestablishes the circuit and arrests the translating means, leav-

ing the translating means in condition for further operation by the closure of the detector switch.

22. In combination, a flow detector operable by flow and water hammer; an alarm means held against operation by current passing therethrough and released for operation when said current is sufficiently reduced; a source of current; lines between said source and means and connecting said alarm means and source in series circuit to hold the alarm means against operation; a normally open detector switch operated by said detector and having its elements connected to said lines respectively and adapted to close to connect said lines, to short-circuit and operate the alarm means; normally open shunting switches connected for shunting said lines respectively, and the elements connected thereto, when the shunting switches are closed, and adapted to be closed by operation of said alarm means when said operation is caused by a break in either of said lines, closure of the shunting switch around the break and reestablishing the circuit and arresting the alarm means, leaving the alarm means ready for further operation by the closure of the detector switch; additional alarm means set in operation by the further operation of the first named alarm means; and means operated by said water hammer to first shunt and then cut out the detector switch element of one line, thereby preventing the operation of said additional means from water hammer after said first named alarm means has been operated by line break.
